UNITED STATES PATENT OFFICE.

CHARLES E. MILLER, OF BELLINGHAM, WASHINGTON.

SAW-SET.

1,131,407.

Specification of Letters Patent.

Patented Mar. 9, 1915.

Application filed March 2, 1914. Serial No. 821,975.

To all whom it may concern:

Be it known that I, CHARLES E. MILLER, a citizen of the United States of America, and resident of Bellingham, in the county of 5 Whatcom and State of Washington, have invented certain new and useful Improvements in Saw-Sets, of which the following is a specification.

This invention relates to means for setting 10 the teeth of saws to different positions or angles with relation to the saw body.

An object of this invention is to provide 15 means for bending or setting the cutting edges of saw teeth to give the same a proper set, means being provided for determining when the tooth has been set to the proper position, and means being furthermore provided for affording a ready and expeditious 20 disengagement of the said mechanism from the saw tooth.

A still further object of this invention is to provide a sawset having a plunger and means associated therewith for setting a saw tooth, means being provided for retaining 25 the plunger and the means associated with it in operative relation while the mechanism is being manipulated.

With the foregoing and other objects in 30 view, the invention consists in the details of construction and in the arrangement and combination of parts to be hereinafter more fully set forth and claimed.

In describing the invention in detail, reference will be had to the accompanying 35 drawings forming part of this specification wherein like characters denote corresponding parts in the several views, and in which—

Figure 1 illustrates a view in elevation of 40 a fragment of a saw with the saw setting device embodying the invention applied thereto; Fig. 2 illustrates a vertical sectional view through the lower portion of the setting mechanism; Fig. 3 illustrates a sectional view on the line 3—3 of Fig. 1 omitting the teeth on each side of the one to which the setting device is applied; Fig. 4 illustrates a perspective view of a housing 45 associated with the plunger; and Fig. 5 illustrates a perspective view of an anti-friction roller to be used in connection with the plunger.

In these drawings 6 denotes a plunger having a recess 7 in one side thereof, the 50 wall of which forms a cam by reason of the fact that the said wall extends inwardly

and outwardly and terminates in a shoulder 8, the same forming a seat for a roller 9 which roller is intended to ride over the cam or inclined surface formed in the manner 60 just stated.

The plunger 6 has a set screw 10 threaded into it, which set screw is designed to limit the movement of the housing with respect to the plunger or vice versa.

The housing to which reference has been made is identified by the reference numeral 11 and is shown as of restricted area at the top as compared with the area of the bottom, that is to say, there is an offset 12 at one 70 side of the said housing and the wall at the opposite side is removed in part, the said housing having lugs 13 extending toward each other and forming with the rear and side walls a restricted channel coextensive 75 in area with the cross sectional area of the plunger, it being understood that the space 14 at the lower portion of the housing is designed for the purpose of receiving a tooth of a saw which is to be operated on by the 80 plunger, roller and housing, when movement of one with relation to the other is effected.

The rear wall of the housing has a screw 15 which screw is provided for the purpose of adjusting the housing with relation to the 85 plunger. When the said screw is moved to enter the housing, it bears against one surface of the plunger and draws the opposite wall of the housing toward the front of the plunger so that the roller is retained in the 90 seal of the plunger and the roller serves to prevent disengagement of the housing from the plunger.

The rear surface of the front wall 16 of the housing is beveled to form a clearance 95 for the tooth which is to be bent by the action of the saw setting mechanism and the rear surface of the front wall 16 is further provided with bearing surfaces 17 on which the ends of the roller 9 ride when there is 100 movement of the plunger with relation to the housing; thus the roller is caused to engage the cam surface of the plunger and the bearing surfaces with the housing when the maximum set of which the mechanism is capable is imparted to the tooth.

I claim—

1. In a saw set, a housing having lugs, a plunger slideable in the housing and guided by the lugs, said plunger having a recess 110 with a beveled wall, a portion of the housing extending beyond the lugs and having

- a wall, the inner side of which is beveled, and a roller fitting in the recesses of the plunger and coacting with the beveled inner wall of the housing to set saw teeth.
- 5 2. In a saw set, a housing, a portion of which is of increased cross sectional area at its lower end, the inner side of one wall of the larger portion being beveled, roller engaging ribs on the inner side of the beveled wall, a plunger in the housing having a recess with a beveled wall, a roller seated in the said recess and adapted to coact with the wall of the housing for setting saw teeth, and means for limiting the movement of the 10 plunger with relation to the housing.
- 15 3. In a saw set, a housing, a portion of which is of increased cross sectional area at its lower end, the inner side of one wall of the larger portion being beveled, roller engaging ribs on the inner side of the beveled wall, a plunger having a recess with a beveled wall, a roller seated in the said recess and adapted to coact with the wall of the 20 housing for setting saw teeth.
- 25 4. In a saw set, a housing, a portion of which is of increased cross sectional area at its lower end, the inner side of one wall of the larger portion being beveled, roller en-
- gaging ribs on the inner side of the beveled wall, a plunger having a recess with a beveled wall, a roller seated in the said recess and adapted to coact with the wall of the housing for setting saw teeth, and means adjustable in the housing for engaging the plunger to hold the housing, roller and plunger in assembled relation. 30
5. In a saw set, a housing, a portion of which is of increased cross sectional area at its lower end, the inner side of one wall of the larger portion being beveled, roller engaging ribs on the inner side of the beveled wall, a plunger slideable in the housing having a recess with a beveled wall, a roller seated in the said recess and adapted to coact with the wall of the housing for setting 35 saw teeth, means for limiting the movement of the plunger with relation to the housing, and means adjustable in the housing for engaging the plunger to hold the housing, roller and plunger in assembled relation. 40
- 45
- 50

In testimony whereof, I hereunto affix my signature in the presence of two witnesses.

CHARLES E. MILLER.
